UNITED STATES PATENT OFFICE

164,174

COOKING RANGE

Richard Bolton Janes, Baldwin Lake, Greenville, Mich., assignor to Gibson Refrigerator Company, Greenville, Mich., a corporation of Michigan

Application August 19, 1950, Serial No. 11,843

Term of patent 14 years

(Cl. D81—4)

To all whom it may concern:

Be it known that I, Richard Bolton Janes, a citizen of the United States, residing at Baldwin Lake, Greenville, in the county of Montcalm and State of Michigan, have invented a new, original, and ornamental Design for a Cooking Range of which the following is a specification, reference being had to the accompanying drawings, forming a part hereof.

In the drawings:

Figure 1 is a perspective view of a cooking range embodying my new design; and

Figure 2 is a cross-sectional view of the upright splash and control panel at the rear of the range top, taken on substantially the line 2—2 of Figure 1.

The dominant features of my design reside in the portions shown in full lines.

I claim:

The ornamental design for a cooking range, substantially as shown and described.

RICHARD BOLTON JANES.
